CLAIM

The ornamental design for hitch-mounted bike rack, as shown and described.

DESCRIPTION

FIG. 1 is a front elevation view of a hitch-mounted bike rack showing our new design;

FIG. 2 is a left side elevation view thereof, it being understood that the broken lines are for illustrative purposes only and form no part of the claimed design;

FIG. 3 is a rear elevation thereof;

FIG. 4 is a right side elevation view thereof;

FIG. 5 is a top plan view thereof; and,

FIG. 6 is a bottom plan view thereof.

FIG. 1

FIG. 2

FIG. 3

FIG. 5

FIG. 6
